ArgentinaApplication March 21, 1934, Serial No. 716,676
In Germany March 25, 1933

6 Claims. (Cl. 123—11)

This invention relates to an arrangement of the working spaces or chambers of machines such as motors, pumps or compressors operating with a gaseous or liquid fluid, in which at least one working space (suction, expansion, pressure or compression space) is moved with the axis of the machine in a circular path concentric with the axis, while the extent of its movements is determined by pistons at both its forward and rear ends, these pistons being mounted on arms sliding in a hollow ring concentric with the machine axis and varying, by positive mutual and relative movement, the capacity of the working space. According to the present invention a slot, 10 which is provided in the hollow ring for the passage of the arms carrying the pistons, is covered by a sliding ring which participates in the movement of the piston lying at the front end of the path of movement of the working space, and cuts off the latter from the space containing the arms. 15

In the accompanying drawings is illustrated an apparatus according to the present invention operating as an internal combustion engine, three alternative constructions of the invention being 20 illustrated diagrammatically.

Figs. 1 to 4 illustrate in transverse section the first arrangement having one working space, said figures representing, in the order named, the intake, compression, expansion and exhaust 25 positions occupied during operation.

Figs. 5 and 6 illustrate the second alternative construction in which three working spaces are provided. The apparatus is shown in transverse section in Fig. 5 and axial section in Fig. 6.

35 Fig. 7 shows the third alternative construction in transverse section.

Fig. 8 is an axial section taken on the line 8—8 in Fig. 1.

In the construction illustrated in Figs. 1—4 a 40 hollow casing A has an opening in the form of a slot X. In the hollow casing A slide two pistons P, P' which form the front and rear closures defining the extent of the working space B. The piston P is mounted rigidly on the outer end of an arm C, the inner end of which is attached to the machine shaft O. The shaft O is mounted by suitable means, not illustrated, carried by the 45 hollow casing body A. The piston P' is mounted on a rod E which is attached by means of a joint E' to an auxiliary arm D formed in one piece with a boss D' rotatable about the shaft O. On the arm C is rotatably mounted a planet pinion F which engages with a crown wheel G fast on the outside of the hollow casing A, the teeth 50 (which are only diagrammatically indicated in

the drawings) of these parts F and G extending over the whole of the peripheries of these parts. Upon the shaft of the pinion F is keyed a crank M, with the pin E' of which is coupled a crank rod H connected at its other end by the joint H' 5 to the auxiliary rod D.

Upon rotation of the planet wheel F and movement thereof along the periphery of the crown wheel G, the crank M rotates with the planet wheel, so that by means of the lever system H, 10 D, E, the piston P' is caused to alternately approach and recede from the piston P. By this alternate approaching and receding of the pistons P and P', the different phases of a working cycle, that is to say the cycle of a 4-stroke motor are 15 obtained. The slot X in the hollow casing A, through which extend the arms C, D carrying the pistons P, P', permits the arms to rotate with the pistons in the hollow ring. The closure or sealing of the hollow ring which serves as the 20 working or expansion chamber is effected by means of a ring I arranged in the suitably shaped slot X of the hollow casing, so as to be capable of sliding on the flange K thereof and this ring is provided with slots through which the arms C 25 and D extend. The slot provided for the arm C is short so that the sliding ring takes part in the movements of the arm C or piston P. The sliding ring I may if desired be secured to the arm C. As will be clear from the drawings the length 30 of the rod E is sufficiently great for the slot I' in the ring I, through which the auxiliary arm D extends, to be out of connection with the working space B even when the pistons P and P' are 35 at their greatest distance from one another (Figs. 1 and 3). If this were otherwise it would give rise to an opening or leak from the working space.

In the construction illustrated in Figs. 1 to 4, 40 of a 4-stroke motor, there occur two working cycles each of four periods during each revolution, intake, compression, working and exhaust, that is to say one complete cycle in each half revolution. The admission of the gas into the hollow casing A takes place through openings L, 45 L' provided therein and the discharge of the burnt gases takes place through the openings N, N'. R, R' indicate spark plugs.

Fig. 1 shows the motor at the end of the intake period. The pistons P, P' are at a distance from 50 one another, so that gas is drawn in through the opening L into the space B between the pistons. On further movements of the pistons in the hollow casing A the piston P' reaches the edge of the inlet opening L, whereby the expansion cham- 55

ber formed between the pistons is closed and the second or compression period, begins.

Fig. 2 shows the motor at the end of the compression period. The shaft O has performed one-eighth of a revolution clockwise from the position shown in Fig. 1, this having been effected by the force of preceding explosions which has been transmitted to the shaft from the piston P through arm C. Simultaneously the pinion 10 mounted on the arm C has rolled along the crown wheel G and rotated about its axis and by means of the crank M, and the parts H, D, E, the piston P' is caused to approach the piston P, so that the gas enclosed in the hollow casing A between the pistons P, P' is compressed. The explosion 15 space is now in the position opposite the ignition plug R by means of which the compressed gas is ignited. The resulting explosion and expansion of the gas forces the piston P further in 20 clockwise direction.

Fig. 3 shows the motor at the end of the explosion or working period. The piston P, in being driven forward to this position by the expansion of the gas, has transmitted the force which acts 25 upon it, to the shaft O by means of the arm C. Meanwhile, the planet wheel F has travelled along the crown wheel G and in so doing has at least to some extent prevented, through the lever system formed by the parts M, H, D, E, a forward 30 movement of the piston P'. In response to the counter-clockwise rotation of the crank M with the pinion F a lengthening of the lever system M, H takes place and the expansion space between the two pistons is increased during the 35 driving forward of the piston P. By the clockwise movement of the piston P the expansion space between the two pistons at the end of the expansion period is in communication with the edge of the exhaust opening N, and when the 40 opening N is uncovered by the piston P as the latter continues to move the exhausting of the burnt gases begins.

Fig. 4 shows the motor at the end of the exhaust period. By the continued rotation of the 45 pinion F in response to further movement of the piston P, the piston P' is again caused to approach the piston P, so that the volume of the working space is reduced and the exploded gases are driven through the opening N. This concludes the last of the four periods of the cycle.

After a half revolution of the piston P in the hollow casing A, the piston P lies in front of the inlet opening L'. Thereafter when the pistons recede from one another, fuel gas is drawn in 55 through the opening L' into the working space, and the first period of a new cycle begins corresponding to that described above with reference to Figs. 1-4.

In the construction illustrated in Figs. 5 and 60 three working chambers or spaces are provided which are connected mechanically one with another by three arms C secured on the shaft O and three planet wheels F, which control the movement of the corresponding piston P' by 65 means of the parts M, H, D and E, each planet wheel F being mounted upon that arm C which appertains to the adjoining working space in advance, in the direction of rotation, of the piston P' controlled thereby. Since the pistons P, or 70 their arms C, are connected fast with the shaft O, their distance from one another remains unaltered. As a consequence, in the arrangement illustrated each of the three working or explosion spaces is at any moment executing a different 75 working period from that of the two other work-

ing spaces. For example in the position illustrated in Fig. 5 the working space 1 is at the end of the intake period whilst the working space 2 is near the end of the exhaust period and the working space 3 is just past the beginning of the working period.

The sealing ring I in Fig. 6, mounted in the hollow casing A, is attached to the piston P or its arm C and rotates therefore with the latter with respect to the hollow casing. The arm C, and also the auxiliary arm D are, as can be seen from the upper half of Fig. 6, fork shaped. The outer end of each arm C extends through the ring I and is connected to the appropriate piston P by means of a pin C'. The inner end of each forked arm C is secured to the motor shaft O. For the sake of clearness another arm C appertaining to another working space is shown in the lower half of Fig. 6 partly broken away, and also one of the auxiliary arms D which is likewise fork shaped. Each of the three auxiliary arms D extends through an opening 4 formed in the packing ring I so far in the direction of rotation that the movement of each auxiliary arm with respect to the related arm C is not impeded. The outer end of each arm D is connected with the appropriate piston P' through a rod E which is attached to the arm by a joint E'. The inner ends of the forked arms D embrace the motor shaft O loosely through the medium of eyes 5.

The fork shape of arm C permits each crank M to be mounted between the limbs of the fork formed by C the two ends of each crank being preferably mounted in the forked arms. Furthermore the fork formation of the auxiliary arms D makes it possible to arrange the end H² of an appropriate crank rod H between the fork limbs. The drive of the cranks M is effected by means of the planet wheels F and F' (Fig. 6) which engage with crown wheels G, G', secured on each side of the hollow casing A. The shaft O rests in bearings U, U' which are carried by the hollow casing A through rods or bars S, S'. The pistons P and the arms C mounted on the motor shaft O function during rotation as a fly wheel to pass the dead centre.

In the construction illustrated in Fig. 7, the arms C are mounted on a partly cut-away disc T keyed upon the shaft O. The auxiliary arms D¹ are secured by means of links D'' on the disc T. The disc T effects a mechanical bracing of the lever system and also serves to carry the shafts of the planet wheels F. The teeth of the planet wheels, as well as those of the crown wheel G with which they engage are indicated diagrammatically only in the drawings. For the purpose of showing clearly the coupling of the auxiliary arms D¹ with the shafts of the planet wheels F through the crank rods H and cranks M, the disc T is shown as broken away at the upper part. Moreover, in this figure the hollow casing A and the inlet and outlet tubes L, L' or N, N' are shown in section and the remaining parts are shown in elevation. Also for the purpose of clearness, of the planet wheels F which lie outside the disc T, those on the side towards the observer, are omitted, as is also a rear disc like T.

I claim:

1. In a machine of the character described, a shaft, a toroidal casing concentric with said shaft and having a continuous slot along its inner periphery, main and auxiliary pistons mounted for movement within said casing, arms carried by said pistons, respectively, and extending radially through said slot, the arm from the main piston

being secured to said shaft, means for effecting relative movements of the pistons and corresponding variations in the capacity of the working space between them, and a sealing member in the form of a complete ring slidably mounted in said slot to seal said casing, said ring being secured to the arm of the main piston for movement therewith.

2. In a machine of the character described, a shaft, a toroidal casing concentric with said shaft and having a continuous slot along its inner periphery, a plurality of pistons arranged in pairs and mounted for movement within said casing, each pair comprising a main and an auxiliary piston, arms carried by said pistons, respectively, and extending radially through said slot, the arms from the main pistons being secured to said shaft, means for effecting relative movements of the pistons of each pair and corresponding variations in the capacity of the working space between them, and a sealing member in the form of a complete ring slidably mounted in said slot to seal said casing, said ring being secured to the arms of the main pistons for movement therewith.

3. In a machine of the character described, a shaft, a toroidal casing concentric with said shaft and having a continuous slot along its inner periphery, main and auxiliary pistons mounted for movement within said casing, arms carried by said pistons, respectively, and extending radially through said slot, the arm from the main piston being secured to said shaft, means for effecting relative movements of the pistons and corresponding variations in the capacity of the working space between them, and a sealing member in the form of a complete ring slidably mounted in said slot to seal said casing, said ring being secured to the arm of the main piston for movement therewith, and said ring being provided with an elongated slot adapted to permit passage therethrough of the arm of the auxiliary piston.

4. In a machine of the character described, a shaft, a toroidal casing concentric with said shaft and having a continuous slot along its inner periphery, a plurality of pistons arranged in pairs and mounted for movement within said casing, each pair comprising a main and an auxiliary piston, arms carried by said pistons, respectively, and extending radially through said slot, the arms from the main pistons being secured to said shaft, means for effecting relative movements of the pistons of each pair and corresponding variations in the capacity of the working

space between them, and a sealing member in the form of a complete ring slidably mounted in said slot to seal said casing, said ring being secured to the arms of the main pistons for movement therewith, and said ring being provided with a plurality of elongated slots adapted to permit passage therethrough, respectively, of the arms of the auxiliary pistons.

5. In a machine of the character described, a shaft, a toroidal casing concentric with said shaft and having a continuous slot along its inner periphery, main and auxiliary pistons mounted for movement within said casing, arms carried by said pistons, respectively, and extending radially through said slot, the arm from the main piston being secured to said shaft, a sealing member in the form of a complete ring slidably mounted in said slot to seal said casing, said ring being secured to the arm of the main piston for movement therewith, and means for effecting relative movements of the pistons and corresponding variations in the capacity of the working space between them, said means comprising a sun gear carried by the casing, a planet pinion journaled in the arm of the main piston and meshing with said sun gear, a crank secured to said planet pinion, and a connecting rod between the crank and the arm of the auxiliary piston.

6. In a machine of the character described, a shaft, a toroidal casing concentric with said shaft and having a continuous slot along its inner periphery, main and auxiliary pistons mounted for movement within said casing, arms carried by said pistons, respectively, and extending radially through said slot, the arm from the main piston being secured to said shaft, each of said arms having a bifurcated portion, a sealing member in the form of a complete ring slidably mounted in said slot to seal said casing, said ring being secured to the arm of the main piston for movement therewith, and means for effecting relative movements of the pistons and corresponding variations in the capacity of the working space between them, said means comprising a pair of sun gears carried by the casing on opposite sides of its axis, respectively, a pair of planet pinions journaled in the bifurcated portion of the arm of the main piston, said pinions meshing with said sun gears, respectively, cranks secured to said planet pinions with a common crank pin disposed between them, and a connecting rod between said crank pin and the bifurcated portion of the arm of the auxiliary piston.

CHARLES EDGARD MARTIN.
